(57) **ABSTRACT**

A door panel includes a frame, a laminate core, a plurality of thermally-insulative connectors, and an exterior skin. The frame defines a portion of an outer periphery of the panel and has an inner section and an outer section positioned, respectively, adjacent inner and outer portions of the panel. The laminate core is positioned between the inner section and the outer section of the frame. The plurality of thermally-insulative connectors connect the inner section and the outer section to the core. The exterior skin covers the frame. The core is a thermal barrier between the inner section and the outer section. The inner section and the outer section are formed from a thermally-insulative material. The core includes an inner layer formed from a thermally conductive material, and two outer layers formed from steel. The thermally-insulative connectors include a thermally-insulative jacket and a fastener positioned within the jacket.

FIG. 3

FIG. 4

FIG. 5

DOOR PANEL WITH THERMAL BREAK

CROSS-REFERENCE TO RELATED APPLICATIONS

This application claims the benefit of U.S. Provisional Application No. 61/172,865, filed Apr. 27, 2009, which is incorporated herein by reference in its entirety.

BACKGROUND OF THE INVENTION

1. Field of the Invention

The disclosure relates generally to door and window panels, and, more specifically, to panels having a thermal break for improved thermal performance of the panel.

2. Description of the Related Art

Many types of panels exists for doors and windows using common types of materials, such as aluminum, wood, steel, and composites thereof. However, each type of material has its own disadvantages/advantages. For example, while a material, such as aluminum, can be formed with high-dimensional tolerances, this material is thermally conductive, and as such, provides poor thermal resistance. Alternatively, other materials, such as wood or plastics, have better thermal resistance, these materials are not as strong as other materials.

New types of sealing/locking systems have been introduced with door panels, which require particular types of edge profiles of the panel, and these profiles cannot be easily provided by certain materials (e.g., wood).

There is, therefore, a need for a door panel that is able to provide the advantages of multiple types of materials in terms of penetration/impact resistance, thermal performance, and the ability to have intricate edge profiles.

BRIEF SUMMARY OF THE INVENTION

Embodiments of the invention address deficiencies of the art with respect to effectively creating a thermally-efficient panel while providing penetration/impact resistance and the ability to have intricate edge profiles. For example, a panel includes a frame, a laminate core, a plurality of thermally-insulative connectors, and an exterior skin. The frame defines a portion of an outer periphery of the panel and has an inner section and an outer section positioned, respectively, adjacent inner and outer portions of the panel. The laminate core is positioned between the inner section and the outer section of the frame. The plurality of thermally-insulative connectors connect the inner section and the outer section to the core. The exterior skin covers the frame. The core is a thermal barrier between the inner section and the outer section. The inner section and the outer section are formed from a thermally conductive material. The core includes an inner layer formed from a thermally-insulative material, and two outer layers formed from steel. The thermally-insulative connectors include a thermally-insulative jacket and a fastener positioned within the jacket.

Additional aspects of the invention will be set forth in part in the description which follows, and in part will be obvious from the description, or may be learned by practice of the invention. The aspects of the invention will be realized and attained by means of the elements and combinations particularly pointed out in the appended claims. It is to be understood that both the foregoing general description and the following detailed description are exemplary and explanatory only and are not restrictive of the invention, as claimed.

BRIEF DESCRIPTION OF THE SEVERAL VIEWS OF THE DRAWINGS

The accompanying drawings, which are incorporated in and constitute part of this specification, illustrate embodiments of the invention and together with the description, serve to explain the principles of the invention. The embodiments illustrated herein are presently preferred, it being understood, however, that the invention is not limited to the 10 precise arrangements and instrumentalities shown, wherein:

FIG. 1 is a front view of a panel in accordance with the inventive arrangements;

FIG. 2 is a cross-sectional, perspective view of the panel;

FIG. 3 is a cross-sectional view of the panel without a skin;

15 FIG. 4 is a cross-sectional view of the panel with a metallic skin; and

FIG. 5 is a cross-sectional view of the panel with a non-metallic skin.

20 DETAILED DESCRIPTION OF THE INVENTION

Referring to FIG. 1, an exemplar panel 10 for use with a door or window is illustrated. The panel 10 can be used with many types of doors and/or windows, such as pocket doors, 25 sliding doors, French doors, entry doors, garage doors, sliding windows, single-hung windows, double-hung windows, casement windows, and awning windows. The panel 10 includes a frame 20 and core 100. Although the panel 10 is not limited in this manner, the frame 20 can define a portion of the 30 outer periphery of the panel 10. Although not limited in this manner, the frame 20 can include separate portions such as a header rail 22, stile rails 24, 26, and a sill rail 28.

The frame 20 is not limited by the material used to the frame 20. For example, the frame 20 can be formed from 35 fiberglass. However, in certain aspects of the panel 10, the frames are formed from an extruded aluminum. Forming the frame 20 from aluminum allows for both high-strength and reduced weight. Additionally, the frame 20 can be formed with an intricate edge profile 25 through, e.g., extrusion of the 40 aluminum. By providing the capability to form intricate edge profiles 25, the panel can be used with new locking/sealing mechanisms.

Referring to FIG. 2, a core 100 is sandwiched between the outer and inner portions 50, 60 of the frame 20. In certain 45 aspects of the panel 10, the core 100 is configured as a break between the inner and outer portions 50, 60 of the frame 20 and the panel 10. For example, the core 100 can be configured as a thermal break. Additionally, the core 100 can be configured as a sound break that reduces the transmission of sound 50 from one side of the panel 10 to another side of the panel 10. Still further, the core 100 can be configured as a physical break that structurally resists impacts against the panel 10 and/or the penetration of objects through the panel 10.

In certain aspects of the panel 10, the core 100 is formed 55 from a single material, such as plastic, steel or glass. However, in other aspects of the panel 10, the core 100 is formed from multiple materials. Additionally, these multiple materials can be combined together, for example, as a laminate.

FIG. 3 illustrates an example in which a combination of 60 different materials is used to form the core 100. In this particular aspect, a layer 120 of a thermally-insulative material, such as plastic (e.g., vinyl) or fiberglass, is sandwiched between two layers 110, 130 of a high-strength material, such as steel or aluminum. Since the thermal-insulative layer 120 65 separates the outer layers 110, 130, the core 100 can act as a thermal break. Additionally, the high-strength outer layers 110, 130 can act as a physical break that resists puncture. An

alternate laminate, for example, could include a layer of high-strength material sandwiched between layers of a thermally-insulative material.

The panel **10** is not limited in the manner in which the core **100** is attached to the frame **20**. However, in certain aspects of the panel **10**, thermally-insulative connectors **30** are used to attach the core **100** to the frame **20**. The thermally-insulative connectors **30** are configured to reduce the transfer of heat from one side of the panel **10** to the other side of the panel **10**.

The panel **10** is not limited as to a particular type of thermally-insulative connector **30**. However, in certain aspects the connector **30** includes a thermally-insulative jacket **34** through which a fastener **32**, such as rivet, is positioned. For example, referring again to FIG. 3, the jacket **34** is positioned within a through-hole **36** that passes between the outer and inner portions **50, 60** of the frame **20** as well as the core **100**. The jacket **34** can cover the thermally-conductive portions of the core **100**, as well as the inner and outer portions **50, 60** of the frame **20**.

The jacket **34** can also serve to thermally-isolate the fastener **32** from the thermally-conductive portions of the core **100**, as well as the inner and outer portions **50, 60** of the frame **20**. In this configuration, the thermally-insulative connector **30** is configured to both attach the core **100** to the outer and inner portions **50, 60** of the frame **20** as well as maintain a thermal break between the outer and inner portions **50, 60** of the frame.

Although not limited in this manner, the panel **10** may include access holes **90** within the frame **20**. The access holes **90** are configured to permit access to the through-hole **36** into which the thermally-insulative jacket **34** is positioned.

Referring to FIGS. 4 and 5, the panel **10** is not limited as to a particular type of exterior skin **200, 210** covering the panel **10**. For example, FIG. 4 illustrates the panel **10** being covered by a metal skin **200**, such as steel. Alternatively, FIG. 4 illustrates the panel **10** being covered by a non-metallic skin **210**, such as fiberglass. The manner by which the skins **200, 210** are connected to the frame **20** is not limited. For example, the skins **200, 210** may be connected to the frame **20** via welding, glue, and/or connectors.

To further reduce the transmission of sound and/or heat from one side of the panel **10** to another side of the panel **10**, insulative material can be introduced into cavities **40, 140** within the frame and between the core and skin **200, 210**, respectively. Materials capable of reducing the transmission of sound and/or heat are well known, and the panel **10** is not limited to any material so capable. For example, open or closed-cell foam may be introduced into the cavities **40, 140**.

What is claimed is:

1. A door panel, comprising:
a frame defining a portion of an outer periphery of the panel and having an inner section and an outer section positioned, respectively, adjacent inner and outer portions of the panel wherein the inner section and the outer section have substantially the same width;
a laminate core positioned between the inner section and the outer section of the frame such that the inner section and the outer section extend parallel to each other along opposite sides of the core;
a plurality of thermally-insulative connectors connecting the inner section and the outer section to the core; and
an exterior skin covering the frame, wherein the core is a thermal barrier between the inner section and the outer section,
the inner section and the outer section are formed from a thermally conductive material,
the core includes
an inner layer formed from a thermally-insulative material, and
two outer layers formed from steel,
the thermally-insulative connectors include a thermally-insulative jacket and a fastener positioned within the jacket.
